UNITED STATES PATENT OFFICE.

HENRY JOSEPH DEAN-OSGOOD, OF LOUGHBOROUGH, ENGLAND, ASSIGNOR TO HERBERT WATSON SULLIVAN, OF LONDON, ENGLAND.

TUMBLER-SWITCH.

1,339,171.

Specification of Letters Patent.

Patented May 4, 1920.

Application filed April 24, 1919. Serial No. 292,265.

To all whom it may concern:

Be it known that I, HENRY JOSEPH DEAN-Osgood, a subject of the King of England, residing at Loughborough, in the county of 5 Leicester, England, have invented certain new and useful Improvements in Tumbler-Switches, of which the following is a specification.

This invention relates to tumbler switches 10 and an important object is to provide a switch of this type which shall have a long quick break combined with a large area of contact with the switch contact-pieces.

Another object is to provide a tumbler 15 switch wherein a switch-arm is mounted to move in a plane transverse to the plane of movement of the tumbler, and is operatively engaged by a leading edge thereof instead of by its end as heretofore.

20 A further object is to provide that the switch-arm shall be locked in its "on" position by an arm provided on the tumbler.

A still further object is to provide a quick-break double-break switch of the tumbler 25 type which is of simple construction, is inexpensive to manufacture and comprises only few moving parts.

To these and other ends, the invention 30 consists in the construction, arrangement and combination of parts described herein-after and pointed out in the claims.

One embodiment of the invention is illustrated by way of example in the accompanying drawing, wherein:—

35 Figure 1 is an elevation of a double break tumbler switch in its "on" position with a portion of an encircling wall of its base removed to show its switch-arm locked against movement in this position.

40 Figs. 2 and 3 are plan views showing the switch in its "on" and "off" positions, respectively, and,

Fig. 4 is a sectional elevation taken on the line 4—4 in Fig. 2 showing the switch with 45 its tumbler and switch-arm in a position midway between "off" and "on."

Like reference letters designate like parts in all the views.

Referring to the drawing, a tumbler A is 50 mounted to rock on a bridge B, which is supported by projections C made integral with a support or base C¹ made of vulcanite or other convenient insulating material having a circumferential wall C². Firmly attached to the tumbler on the under side

thereof is a cranked actuating arm D, the leading edge of the depending portion D¹ of which is arranged to coact with an inclined face E¹ of a V-shaped recess or gap formed in a porcelain ring E. A recess or groove 60 E² is cut in this face.

Fastened to the ring E by two screws E⁴ is a switch blade F having projecting ends F¹ arranged to engage fixed contact-pieces G of the clip type. These contact-pieces G 65 are prevented from any tendency to move in a counter-clockwise direction as viewed in Figs. 2 and 3, by butting against the projections C. They are fixed to the base C¹ each by a binding-post G¹ which is provided with 70 a threaded portion terminating in a recess in the base C¹ where it is secured in position by a circular nut. The binding-posts G¹ are provided with the usual screws G² which serve to clamp the connecting wires. The 75 switch-arm of the switch is thus constituted by the ring E and the switch-blade F which is arranged to make and break contact with the contact-pieces G.

A pivot for the switch-arm is provided in 80 the form of an internally and externally threaded pillar H, having upper and lower portions separated by a flange H¹ made integral with it. The pillar H is prevented from rotating by means of a circular nut J, 85 which is screwed on its lower end and is situated in a recess J¹ in the base C¹. The flange H¹ prevents axial movement of the pillar.

Lying snugly in an annular space between the pillar H on the one hand and the ring E and blade F on the other hand is a spiral spring L, one end of which is made fast to the flange H¹ and the other to the ring E. Axial movement of the switch-arm is prevented by a screw M screwed into the top of the pillar H. The head of this screw is turned down at N to provide a bearing for the ring E. It will be seen that the point about which the tumbler A can 100 rock is situated in the axis of rotation of the switch-arm.

The operation of the described tumbler switch is as follows:—

When the tumbler A is moved from the 105 "off" position shown in Fig. 3 to the "on" position shown in Fig. 2, the leading edge of the portion D¹ of the arm D co-acts with the inclined face E¹ of the ring E and rotates the switch arm about the pillar H in a 110

counter-clockwise direction, until the contact-pieces F^1 are brought into engagement with the switch contact-pieces G . The spring L is loaded at the same time.

5 As this movement proceeds the end of the portion D^1 of the arm D slides up the inclined face E^1 as shown in Fig. 4, and finally takes into the groove E^2 in this face as shown in Fig. 1. The switch-arm is then 10 locked in its "on" position.

If the tumbler is now rocked back to the "off" position, the end of the portion D^1 will be disengaged from the groove E^2 and the spring L will return the switch-arm into 15 the position shown in Fig. 3. Should this spring fail to remove the switch-arm from the fixed contact-pieces for any cause, however, then the portion D^1 will coat with a face E^3 of the gap in the ring opposite the 20 face E^1 , and will rotate the ring E , thus positively moving the switch-arm out of engagement with the fixed contact-pieces G , the spring L still causing a quick break.

Important advantages of a switch constructed as described above over existing tumbler switches are the long quick break obtainable, the increased area of contact between the fixed and moving contact-pieces, and the more mechanical action effected by 25 mounting the switch-arm on a pillar instead of relying on a toggle movement as heretofore.

What I claim as my invention and desire to secure by Letters Patent is:—

35 1. In a switch of the type described, the combination with a support, and a contact-piece mounted thereon, of a switch-arm having an inclined face rotatably mounted on the base and arranged to make and break 40 contact with said contact-piece, and a tumbler that is mounted to rock on said sup-

port in a plane transverse to the plane of rotation of the switch-arm and is provided with an actuating arm having a leading edge arranged to coat with the said inclined face to rotate the switch-arm into contact with said contact-piece. 45

2. In a switch of the type described, the combination with a base, and a contact-piece mounted thereon, of a switch-arm having a recessed inclined face rotatably mounted on the base and arranged to make and break contact with said contact-piece, and a tumbler that is mounted to rock on 50 said base in a plane transverse to the plane of rotation of the switch-arm and is provided with an actuating arm arranged to coat with the said inclined face and enter into the recess therein to rotate the switch-arm into, and to arrest the same in, contact with said contact-piece. 55

3. In a switch of the type described, the combination with a support, and a contact piece mounted thereon and a switch arm having a lateral V-shaped recess rotatably mounted on the support and arranged to make and break contact with said contact piece, of a tumbler that is mounted to rock on said support in a plane transverse to the plane of rotation of the switch arm and is provided with a cranked arm having a leading edge arranged to operatively engage directly with one side of said recess to rotate the switch arm in one direction, and having an opposed edge arranged to operatively engage directly with the other side of said recess to positively rotate the switch arm in the opposite direction, substantially 65 as described. 70

In testimony whereof I affix my signature. 75

HENRY JOSEPH DEAN-OSGOOD.
